FIREARM

Louis Marquis, Jr., Wuppertal-Elberfeld, Germany, assignor to Richard Goldberg, Wuppertal-Elberfeld, Germany

Application May 25, 1934, Serial No. 727,559
In Germany May 27, 1933

6 Claims. (Cl. 42-1)

This invention relates to a fire-arm of novel construction. Fire-arms are already known in the form of a box-like casing, which can be fitted to a belt or the like. With such casings the cartridge container has already been constructed in the form of a ring mounted upon the casing of the weapon, this ring being provided with a number of cartridge chambers. In all the known constructions the operating of this weapon is effected by the aid of a rather long flexible connection, such for example as the device marketed under the name of Bowden cable, which is seized or pulled up by hand or else by the aid of a pressure release located at the end of a rather long flexible tube.

According to this invention a substantial improvement in such weapons secured to a belt is obtained by providing on the casing of the weapon a cock or trigger, which may be constructed in the manner of trigger cocks that are usual in guns, revolvers or the like. The trigger may advantageously be arranged in the end of the casing, so that it moves in a plane horizontally parallel to the front surface of the casing, while by means of suitable connections the movement of the striker proceeds transversely to this direction, and the ball accordingly also leaves the weapon transversely to the front surface of the casing.

A further improvement in the weapon according to the invention is obtained by providing it with an absolutely firm and undisplaceable seat in the belt, and by shaping it like a coupling lock, so that it forms at the same time the closure of the girdle or belt. For this purpose the rear wall of the casing may be provided with the necessary hooks and eyes for securing it to a belt, such as those worn on military service. Alternatively the weapon may be secured, by the aid of suitable fastening means, such as barriers or the like, preferably in a readily releasable manner, but firmly and undisplaceably, upon a shoulder belt lock.

Further improvements comprised in this invention relate to the special construction of the members transmitting the movement of the trigger to the striker and also of the members effecting the conveyance of the cartridge chamber, the return of the striker and of the trigger, the protection of the weapon, and so forth.

One form of construction of a small fire-arm according to the invention is illustrated by way of example in the accompanying drawings, in which

Figure 1 shows the weapon as seen from the front,

Figure 2 is a side view of the weapon,

Figure 3 shows the interior of the weapon casing after removal of the back wall partly in section,

Figure 4 is a section on the line 4-4 in Fig. 3,

Figure 5 is a section on the line 5-5 in Fig. 3,

Figure 6 is a section on the line 6-6 in Fig. 3,

Figure 7 is a section on the line 7-7 in Fig. 3,

Figure 8 is a front view of the weapon with the cartridge chamber removed, and

Figure 9 is a back view of the weapon casing.

In these drawings the reference numeral 1 denotes the front wall of the casing, which is of flat construction, 2 and 3 denote the side walls thereof. 4 is the upper transverse wall, and 5 the lower transverse wall. The weapon casing therefore forms a flat box, open towards the rear. In a rearward direction, that is to say, towards the surface of the body belt, this box is closed by a wall, which is secured to the casing for instance by the aid of lugs 7, 8, and so forth, engaging upon the casing 1. The rear wall is according to the invention preferably provided with a clip 9, through which the belt is passed, with a tongue or prong 10 for engaging in the holes in the body belt, and with eyes 11 and 12 for engaging the free end of the belt. This construction of the weapon, resembling that of a coupling lock, may be such that the same admits of being provided in place of an ordinary coupling lock on the leather belt or girdle.

On the casing 1 of the weapon is secured on the front an annular cartridge chamber 13, by means of screws 14 for example, upon the smooth shank portion 15 of which the cartridge chamber can rotate. Cylindrical bores 16, 17 and so forth in the cartridge chamber serve for the reception of cartridges 18, which are introduced into the cartridge chamber after releasing the screw 14 and removing the cartridge chamber from the back. The cartridges may, if desired, alternatively be introduced from the side and secured in position by a superposed ring.

The ignition of the cartridges is effected by driving forward a striker pin 19, which in its turn is set in operation by the movement of the trigger 20. The movement of the trigger is here transmitted to the striker pin 19 by the aid of a slide bar 22. The rotation of the magazine 13 for the purpose of conveying a fresh cartridge in front of the striker pin is likewise effected by the aid of a loading transporter 21, also actuated by the movement of the trigger.

In detail the co-operation of the essential members hereinbefore mentioned is accomplished with the assistance of various further auxiliary members in the following manner:—

5 The trigger 20, which is rockable about its pivot 24 in a cavity 23 in the casing wall 2, is provided with three lever-like cams 25, 26 and 27. After the safety hook 28 has been rocked up by pressure upon the toothed head 29 of the safety device, the locking bar 22 is set free, for the action of the trigger. Now if the trigger 20 is moved in the direction of the arrow A in Figure 3, the cam 25 drives the locking bar 22 forwards in the direction of the arrow, until the cam 25 10 reaches the position 25' shown in dotted lines. Here the striker pin lever 32, which is rockable about a pivot 33, is pressed by the action of a compression spring 36 into the recess of the locking bar 22 in front of a wedge surface 31. At the same time the striker pin 19 goes back into the 15 interior of the casing. Then the spring 30, which has been stressed by the forward moving of the locking bar 22, drives the locking bar back. Under these circumstances the inclined surface 31 20 of the locking bar pushes against the upper portion of the striker pin lever. The striker pin lever 32 is therefore pushed back in the direction of the arrow in Figure 4, and accordingly the tip 19 of the striker pin is thrown forward. It then strikes the bottom of the cartridge 35 and 25 discharges the shot. In order to obviate an excessive recoil of the locking bar 22 under the influence of the spring 30 its movement is limited by a pin 38 projecting into the locking bar recess. 30

The backward movement of the trigger 20 is effected by the action of a blade spring 39, which bears against the cam 27. In its backward movement the cam 25 moves away from the end wall 40 or cap 41 of the locking bar 22, which is rockable about a pivot 40, and which, after the passage of the cam 25, is returned by a spring 42 into its original position. 45

The cartridge chamber 13, which, in the closed position, is arrested by a bolt 45 controlled by a spring 43 and provided with a rounded head 44, is transported by the trigger cam 26 when the trigger 20 is pulled; for the cam 26 bears upon a rotatable arm 46, in which is supported the 50 transport locking bar 21 already mentioned. The transport locking bar 21 acts upon one tooth 47 in a group of teeth projecting rearwards out of the cartridge chamber 13 into a segmental cavity 48 in the casing wall 1. Following the movement of the cam 26, the transport locking bar 21 presses the tooth 47 so far downwards that the next cartridge moves into a position in front of the 55 striker pin. In this position the bolt 45, which had been pressed back during the rotary movement of the cartridge chamber, arrests the cartridge chamber afresh. The return of the arm 46 and of the transport locking bar 21 is then effected by a blade spring 49, which may if desired be made in one piece with the spring 39. The transport locking bar 21, which is so supported in the arm 46 as to be movable by a spring 50, then slips past the next upper tooth of the cartridge chamber 13, and takes up a position in the gap between this tooth and the next one. Thus all the parts of the weapon have returned 60 into their original positions. Upon the head 29 of the safety device being released, the hook 28 of the safety device falls down, so that the weapon is again in the safety position. 51 denotes a 65 spring pin, which enters an aperture 52 in the

rear wall 6 and serves as an arresting means for the rear wall.

The invention may be modified in construction and design in a variety of ways without departing from the basic idea. The exceedingly flat 5 shape of the weapon casing, which in other respects may be of any desired design, for instance round or hexagonal, and which enables the weapon to be constructed and employed as a belt lock, is in any case essential, and is rendered 10 possible by the transverse arrangement of the transmission means between the trigger and the striker bolt and of the charge transporter. Other points of particular importance are: The lever-like construction of the trigger in the manner of 15 the known gun triggers, and the device described for transporting and arresting the cartridge chamber, as well as for returning the moving parts. The supplying of the cartridges may however if desired be effected in another way, by 20 belts for example. In practice the weapon may do good service to all officials or other persons employed in watching, for instance factory watchmen, transport conductors, registered letter carriers, cyclists, motor cyclists, and the like. 25

Instead of ball cartridges this weapon may also be equipped for firing blank cartridges, percussion caps or the like.

For the purpose of diminishing the recoil, the 30 belt or the rear wall of the casing may be widened or supported. The weapon may also be provided with automatic release and actuation for a continuous succession of shots. Furthermore the weapon can also be employed for shooting 35 paint or other liquid substances.

Having now particularly described and ascertained the nature of my said invention and in what manner the same is to be performed, I declare that what I claim is:—

1. A fire-arm in the form of a box-like casing 40 having a removable rear wall and having an aperture in one side wall, a rotatable ring-shaped cartridge chamber arranged in the front of the casing and out of which the shot passes transversely to the front wall of the casing, members 45 on the removable rear wall of the casing adapted for securing the casing to an ordinary sword-belt clasp, means for discharging the fire-arm including a lever trigger pivotally arranged in the aperture in the side wall of the casing in such a way that its rotary movement is effected in the central plane of the casing, a transversely movable striker-pin lever, a longitudinally slidable locking bar having a bevelled surface for actuating the striker-pin lever, the movement of the trigger being transmitted to the striker pin lever by means of the locking bar, the rear face of the cartridge chamber having a circular series of teeth, a tooth engaging member, the trigger 60 lever being provided with a cam-like projection pressing in its turning upon the tooth engaging member for rotating the cartridge chamber, and a spring locking bolt for arresting the movement of the cartridge chamber in the shooting position. 65

2. A fire-arm in the form of a box-like casing having a removable rear wall and having an aperture in one side wall, a rotatable ring-shaped cartridge chamber arranged in the front of the 70 casing and out of which the shot passes transversely to the front wall of the casing, members on the removable rear wall of the casing adapted for securing the casing to an ordinary sword-belt clasp, means for discharging the fire-arm in- 75

- cluding a lever trigger pivotally arranged in the aperture in the side wall of the casing in such a way that its rotary movement is effected in the central plane of the casing, a transversely movable striker-pin lever, a longitudinally slidable locking bar having a bevelled surface for actuating the striker-pin lever, the movement of the trigger transmitted to the striker pin lever by means of the locking bar.
- 5 3. A fire-arm in the form of a box-like casing having a removable rear wall and having an aperture in one side wall, a rotatable ring-shaped cartridge chamber arranged in the front of the casing and out of which the shot passes transversely to the front wall of the casing, members on the removable rear wall of the casing adapted for securing the casing to an ordinary sword-belt clasp, means for discharging the fire-arm including a lever trigger pivotally arranged in the aperture in the side wall of the casing in such a way that its rotary movement is effected in the central plane of the casing, a transversely movable striker-pin lever, a longitudinally slid- 10 able locking bar having a bevelled surface for actuating the striker-pin lever, the movement of the trigger being transmitted to the striker pin lever by means of the locking bar, the free head of the trigger lever being provided with three cam-like projections, the first of them actuating the pivotally movable cap of the locking bar, the second of them actuating the tooth engaging member for rotating the cartridge chamber, the third of them being pressed by a spring.
- 15 5. A fire-arm in the form of an extremely flat box-like casing having a removable rear wall and having an aperture in one side wall, a rotatable ring-shaped cartridge chamber arranged in the front of the casing and out of which the shot passes transversely to the front wall of the casing, members on the removable rear wall of the casing adapted for securing the casing to an ordinary sword-belt clasp, means for discharging the fire-arm including a lever trigger pivotally arranged in the aperture in the side wall of the casing in such a way that its rotary movement is effected in the central plane of the casing, a transversely movable striker-pin lever, a longitudinally slid- 20 able locking bar having a bevelled surface for actuating the striker-pin lever, the movement of the trigger being transmitted to the striker pin lever by means of the locking bar, the rear face of the cartridge chamber having a circular series of teeth, a tooth engaging member, the trigger lever being provided with a cam-like projection, pressing in its turning upon the tooth engaging member for rotating the cartridge chamber.
- 25 30 4. A fire-arm in the form of a box-like casing having a removable rear wall and having an aperture on one side wall, a rotatable ring-shaped cartridge chamber arranged in front of the casing and out of which the shot passes transversely to the front wall of the casing, members on the removable rear wall of the casing adapted for securing the casing to an ordinary sword-belt
- 35 35 6. A fire-arm as claimed in claim 5, wherein a safety hook is provided for engagement with the locking bar said hook being provided with an actuating head, substantially as and for the purposes set forth.
- 40 LOUIS MARQUIS, JR.
